BUCKLE

Lloyd A. Straits, United States Navy

Application June 19, 1942, Serial No. 447,670

3 Claims. (Cl. 24—192)

(Granted under the act of March 3, 1883, as
amended April 30, 1928; 370 O. G. 757)

This invention relates to a buckle, and has for an object to provide an improved buckle especially adapted for use on a pneumatic life-saving belt.

It is an object of this invention to provide a buckle which may be used in connection with a pneumatic life-saving belt so as to adjust the size of the belt to the individual wearing the same without any danger of puncturing the belt and destroying its efficiency for life-saving purposes.

A further object of this invention is to provide a belt buckle which may grip the pneumatic tube of the life-saving belt in such a fashion that there is no danger of injuring the tube, while at the same time it holds the tube securely so that it may remain properly about the body of the wearer.

A further object of this invention is to provide a buckle for a life-saving belt wherein the buckle will hold the belt securely in position about the body of the wearer and which may be easily and quickly operated when the belt is to be inflated so as to permit the belt to enlarge under pressure of inflation, and at the same time increase its diameter so that it may move from the waist portion to a position about the chest under the arms of the wearer.

A further object of this invention is to provide a belt buckle that may be made inexpensively, being preferably formed of flat sheet metal, suitably stamped and pressed to the desired shape, thus providing simplicity and low cost of construction and assembly. Although sheet metal is the easiest and simplest material to be used, it will be obvious that the belt may be formed of any other suitable material, including moldable plastics.

With the foregoing and other objects in view, the invention consists in the construction, combination and arrangement of parts hereinafter described and illustrated in the drawing, in which:

Fig. 1 is an elevational view of a fragment of a pneumatic life-belt with the buckle of this invention applied thereto.

Fig. 2 is a sectional view on line 2—2 of Fig. 1, with the buckle lever in released position.

Fig. 3 is a fragmentary sectional view similar to Fig. 8, but with the buckle lever in clamping position.

Fig. 4 is an elevational view similar to Fig. 1 of a slightly modified form of this invention.

Fig. 5 is a bottom plan view of Fig. 4; and

Fig. 6 is a partly edge view of Fig. 4.

There is shown at 10 a hollow tube forming the pneumatic life belt to which the buckle 11 of this invention is to be applied. This buckle 11 includes a base 12 of a length slightly greater

than the width of the belt 10 and is provided with a pair of upstanding ears 13. Extending substantially centrally of the base 12 between ears 13 is a rounded depression 14. Pivoted on the ears 13 by means of integrally extending pintles 15 journaled in suitably aligned apertures 16 is the buckle lever 17 provided with a handle finger 18.

It will be observed from Figs. 2 and 3 that the apertures 16 in the ears 13 are located substantially centrally of the depression 14. The buckle lever 17 extends somewhat beyond the pintles 15 and terminates in a rounded portion 20, this rounded portion 20 thus rotating about the pintles 15 and apertures 16 as a center when the buckle lever 17 is raised by means of its handle finger 18. The belt 10 extends over the base 12 above the rounded depression 14 and below the rounded portion 20 of buckle lever 17. When the buckle lever 17 is raised, as shown in Fig. 2, the rounded portion 20 is raised above the belt 10 and leaves it free to slide over the base 12, but when the lever 18 is brought to the position shown in Figs. 1 and 2, the rounded portion 20 presses the top of belt 10 firmly into the depression 14, holding the belt against movement therethrough.

The ears 13 are provided with a second pair of aligned apertures 21 in which are journaled pintles 22 of a buckle hook 23. This buckle hook 23 is provided with an extending hook finger 24 having a hook portion 25 adapted to cooperate with a bail member 26. The bail member 26 is provided with a central recess 27 for keeping the hook portion 25 centralized. The bail member 26 is adapted to be secured in the other closed end of the belt 10, this closed end of the belt 10 being secured about the cross bar 28 of the bail member 26.

In the form of the invention shown in Figs. 4, 5 and 6, instead of having a separate buckle hook pivoted on the ears 13, there is provided a buckle hook 31 which integrally extends from the base 12. This buckle hook 31 is provided with a reverse hook shaped portion 32 to cooperate with an eye 33 in the tongue 34 extending from a bail member secured to the closed end of the life belt. In this form the buckle lever 17 is identical in construction and operation with that shown in Figs. 1, 2 and 3, and no detailed description thereof is therefore deemed necessary. To insure against accidental separation of the buckle hook from its bail eye, the buckle hook is provided with a raised boss 35, while the hook portion 25 and hook portion 32 are each provided with an upwardly extending edge 36 cooperating therewith. In operation, the hook portion is placed

through the eye of the ball member and then the buckle is drawn tightly, the buckle lever 17 being held in the raised position shown in Fig. 2 while this is being done. The buckle lever 17 is then lowered to the position of Figs. 1 and 3, thus holding the belt in position about the waist of the wearer. When ready to inflate the belt for operation, in any conventional manner as by lung inflation or by carbon dioxide capsules, the finger piece is raised, releasing rounded portion 20 out of contact with the belt 10 and permitting it to slide through the buckle as the belt is inflated after the wearer is in the water. This permits the belt to be inflated and at the same time permits its diameter to increase, whereupon the belt floats upwardly to a position under the arm of the wearer, thus supporting the wearer in good floating position with head out of the water.

The end of the belt, not shown, is closed and provided with an enlargement of any suitable nature, preventing the end from sliding through the belt.

Other modifications and changes in the proportions and arrangement of the parts may be made by those skilled in the art without departing from the nature of the invention, within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

1. A device for adjustably fastening an easily puncturable inflatable belt consisting of a buckle comprising a base member having a transverse rounded depression therein strengthening the base member against bending, upstanding ears at the ends of said base member, a clamping lever, a rounded portion on the end of said lever, pintle means on said clamping lever for pivoting said clamping lever in said upstanding ears of said base member with said rounded portion eccentric to said pivoting means, whereby said

5 clamping lever will move said rounded portion to and from cooperating position with the transverse depression in the base member to clamp the belt therebetween, hook means extending from said base member, and a hook cooperating bail member adapted to be secured to an end of the tube.

10 2. A device for adjustably fastening an easily puncturable inflatable belt consisting of a buckle comprising a base member having a transverse rounded depression therein strengthening the base member against bending, upstanding ears at the ends of said base member, a clamping lever, a rounded portion on the end of said lever, pintle means on said clamping lever for pivoting said clamping lever in said upstanding ears of said base member with said rounded portion eccentric to said pivoting means, whereby said clamping lever will move said rounded portion to and from cooperating position with the transverse depression in the base member to clamp the belt therebetween, hook means extending from said base member, and a hook cooperating bail member adapted to be secured to an end of the tube, said hook being pivoted to said upstanding ears of said base member.

15 20 25 30 35 40 45 3. A device for adjustably fastening an easily puncturable inflatable belt consisting of a buckle comprising a base member having a transverse rounded depression therein strengthening the base member against bending, upstanding ears at the ends of said base member, a clamping lever, a rounded portion on the end of said lever, pintle means on said clamping lever for pivoting said clamping lever in said upstanding ears of said base member with said rounded portion eccentric to said pivoting means, whereby said clamping lever will move said rounded portion to and from cooperating position with the transverse depression in the base member to clamp the belt therebetween, hook means integrally extending from said base member, and a hook cooperating bail member adapted to be secured to an end of the tube.
